UNITED STATES PATENT OFFICE.

RALPH WHITE, OF PHILADELPHIA, PENNSYLVANIA, ASSIGNOR TO EDWARD G. BUDD
MANUFACTURING COMPANY, OF PHILADELPHIA, PENNSYLVANIA, A CORPORATION
OF PENNSYLVANIA.

RIVETED JOINT.

1,299,275.

Specification of Letters Patent.

Patented Apr. 1, 1919.

Application filed March 20, 1918. Serial No. 223,603.

To all whom it may concern:

Be it known that I, RALPH WHITE, a citizen of the United States, residing at 333 N. 52nd St., Philadelphia, in the county of 5 Philadelphia and State of Pennsylvania, have invented new and useful Improvements in Riveted Joints, of which the following is a specification.

The invention relates to riveted joints or 10 constructions, and has for an object to provide a simple, cheap and effective method and structure for securing a material to another material, such as a surface or body of metal in one operation and to effectively 15 secure the material against displacement.

More particularly this invention comprehends a means of establishing a joint in a surface or body of metal or the like to secure to the surface or body a sheet or sheets 20 of material, in instances where it is impossible to secure behind the body a suitable backing to receive the blow of the hammer or tool which drives the securing element into place as, for instance, in the securing of 25 leather or composition leather to the inner side of the door of an automobile. In an instance of this character it is not ordinarily possible to effectively secure a sheet of leather to the inner face of the automobile 30 door after the door has been finished and the metal construction thereof completed, for the reason that the door consists of an outer metallic surface, and the inner metallic surface or body mentioned, and to which the 35 sheet of material is to be secured, and therefore it is impossible to arrange behind the place of arrangement of the rivet, a suitable backing to receive the blow of the hammer or tool, for the reason that the outer and 40 inner sides of the door form practically a closed chamber which does not permit of the insertion of an anvil or plate that can be held against the inner face of the inner side of the door to receive the blow on the securing 45 element, and permit of the securing element being driven into place and deflect the prongs of the securing element so that the securing element will perform its function, namely, that of securing the sheet of covering leather or material in place.

I am aware that various forms of fastening devices for rivets and other securing elements have been used heretofore to deflect the inner ends of the prongs of the rivets 55 or the securing elements, but in these in-

stances it is either necessary to place an anvil or blow-receiving plate behind the material through which the rivet passes, so as to deflect the prongs; hammer or deflect the prongs by means of a tool after the rivet has 60 been driven into place, or associate with the metal through which the rivet passes, a separate plate or sheet of material which will cause the deflection of the prongs of the rivet when it is driven home. All of these 65 constructions are impractical in connection, for instance, with the securing of a leather sheeting to the inner side of an automobile door, and unless an additional anvil or plate is arranged behind the inner wall, the leather 70 sheeting cannot be riveted to the inner side or face of an automobile door in which the metal work has been completed. Therefore, where it is necessary to rivet the sheet of 75 material to the inner side of the automobile door, before the completion of the metal work thereon, it will be obvious that the leather would be disfigured, marred and scratched by the subsequent use of tools and machinery to complete the metal work of 80 the door. For this reason it is most desirable that the leather for the outer face of the inner side of the door be secured thereon after the door has been completed, and this is also a very necessary arrangement in instances where old and worn leather is removed from the inner side of a door to be 85 replaced by a new layer or sheeting of leather. In such a case it would be necessary to tear the sides of the door apart in 90 order to rivet the new sheeting thereto, in order that a suitable backing could be obtained to receive the blow of the tool on the rivet, and deflect the prongs thereof.

With my invention I form a backing or 95 deflecting plate integrally with the inner side of the automobile door by striking a portion of the automobile door outwardly or inwardly from itself to form the plate, and thus in the arrangement of the securing 100 element to a construction of this kind to secure a sheet of leather or other material to the face, I do not have to employ any extra backing plates, washers or other devices, and by simply hammering home the securing 105 element I cause it to pass through the sheet of material, the body or face of the door, and finally bring about the deflection of the prongs of the securing element after they have passed through the necessary faces or 110

sheets of material that are to be secured together by the securing element.

In the further disclosure of the invention, reference is to be had to the accompanying drawings, constituting a part of this specification, in which similar characters of reference denote corresponding parts in all the views, and in which—

Figure 1 is a fragmentary elevation of 10 the inner side of an automobile door, showing a sheet of material secured thereto by my form of construction.

Fig. 2 is a view looking at one end of the structure shown in Fig. 1.

Fig. 3 is a horizontal sectional view taken 15 on the line 3—3 in Fig. 1.

Fig. 4 is a fragmentary view looking at 20 the outer face of the inner side of the door, with the sheet of material removed and the head of the securing element severed therefrom, to show in greater detail the arrangement of the prongs of the securing element, and

Fig. 5 is a similar view of the inner side 25 of the door looking at the outer face thereof, showing the form of construction prior to the arrangement of the securing element thereon.

Referring more particularly to the view, 30 10 indicates an automobile door which is formed of an outer side 11 and an inner side 12, both preferably being of pressed metal, and thus practically forming a closed compartment 13, when the usual material 35 such as leather, indicated by the numeral 15, is secured to the inner side and which, as shown in this instance, may be in the nature of a circumferential edge 16. Further, a leather flap 17 may be provided 40 to form a closure for an opening 18 in the sheet of leather so as to form the chamber 13 which may be adapted for the reception of various articles or tools. As shown in Fig. 2, the outer side 11 is bent 45 around to form the edge 16 which I also term the inner side 12, and as mentioned heretofore, when the sheet of material 15 is secured to the edge 16 the closed compartment will practically be provided, except 50 for the addition of a flap 17 to cover an opening in the sheet of leather so as to form an entrance to the compartment, it being understood of course that the edge 16 may be continued to form a complete inner side 55 12, if desired, and that the sheet of leather can be secured to the edge or the inner side, as the case may be.

Taking into consideration one of my units of construction, I subject the edge 16 to 60 pressure to strike rearwardly therefrom and toward and into the chamber 13, a plate 19 which I preferably term a backing and deflecting plate, said plate having a central forwardly projecting hump 20 and curved 65 deflecting portions 21, thus also providing

opposed slots or openings 22 in the edge 16. It will be understood that any suitable form of tool could be provided to form the opposed slots or openings, and in so doing the passage of the tool through the metal 70

would bend the portion of the latter between the openings so as to form the hump 20 and the curved deflecting portions 21. Thus when the inner side or edge 16, as the case

may be, is formed with a backing and a 75 deflecting plate as described, it will be clear that the metal work of the automobile door can be completed by attaching the inner side to the outer side, or where they are formed in one piece by attaching any other 80

metal work to the door that may be necessary, before the sheeting of leather is placed on the inner side or edge, and it will be seen that the inner side when formed with the openings and backing and deflecting 85 plate as mentioned, will appear as in Fig. 5. The sheet of leather or other material 15 is now placed against the inner side of the door so that the edge thereof will overlap or project over and cover the edge 90 16, forming a part of the inner side of the door, and when this has been accomplished a securing element 23 of any standard form

of construction, and having the usual prongs 95 24 and head 25, is driven through the sheet of material 15 with the points of the prongs

engaging and deflecting over the hump 20. As the securing element is driven home the deflected prongs will engage the curved deflecting plates 21, and they will deflect the 100 prongs outwardly and curve the same through the openings 22 back toward the inner face of the edge 16, thus causing the head of the securing element to be brought tightly against the face of the sheet of 105 leather, thus effectively securing the sheet of leather to the inner edge of the automobile door. It will be seen that with this arrangement it is not necessary to secure an anvil or backing plate against the 110

inner face of the edge to deflect the prongs of the securing element, to receive the blow of the hammer or tool upon the securing element, as is ordinarily the case when a securing element is driven home for, in this 115 instance, I provide a unitary integral construction, in that the backing and deflecting plate is formed as an integral part of the edge, supporting the sheet of leather and securing the securing element, and thus with 120 a construction of this character a sheet of leather can be applied to an automobile door with a minimum amount of work and material, and without damage to any part of the door or other structure to which it 125 may be desired to attach a sheeting of any kind, where it is impossible to secure a suitable backing to relieve the blow of a hammer or tool.

Although I have described and shown a 130

particular form of my invention, it will be understood that I do not limit myself thereto; that various slight changes may be made without departing from the spirit of the invention, the scope of which is defined in the 5 appended claim.

I claim—

A box like structure such as an automobile door, consisting of outer and inner side 10 plates, the inner plate being provided with

end slits and an integral intermediate hump having curved deflecting portions, and a split and headed rivet having its prongs passing through a leather lining and into the slits, the ends of the prongs being deflected and clenched by the deflecting portions of the hump by the act of driving the rivet. 15

In testimony whereof I affix my signature.

RALPH WHITE.
